FIG. 1

FIG. 2

FIG. 3

Inventor

JOHAN L. HARMSEN

by: Frank J. Pijan.

POWER RAIL SUPPORT AND SHIELD

This invention relates to support members for power or third rails and means for shielding such rails and is particularly directed to support members having simple means by which protective shields may be secured thereto.

It is becoming increasingly common to employ fiberglass reinforced polyester or similar moldable materials for insulating support members of third rails used to supply electric power for rapid transit systems. The line voltage in the power rail is frequently in the order of 600 volts or higher and therefore such rails must be adequately shielded to reduce the hazard of anyone accidentally touching the rail. In addition, it is desirable to shield the rail as much as possible from weather conditions (rain, snow and freezing rain).

Conventionally, power rails are shielded by lengths of timber which are secured to the top and side of each support member by bolts. Projecting bolt heads are undesirable both from the stand point aesthetics and the stand point of safety since such heads frequently constitute a dangerous obstruction. In addition bolts may become loose and eventually fall onto the power rail.

It is accordingly an object to provide a support member having a groove and recess adapted to receive the ends of protective shields and removably secure the protective shields thereto without the necessity of bolts or screws.

It is another object to provide a support member and shield which may be conveniently formed of reinforced polyester or similar moldable materials and which may be quickly and easily assembled with a minimum of effort.

It is another object to provide a shield which may be connected to a support member by means of a single pin.

Another object of the present invention is to provide a support member, shield combination having no projections in the path of the collector shoe which constitute a hazard.

These and other objects are accomplished by providing a support member for supporting a power rail and a rail shield and adapted to be secured to a railway crosstie, or the like base structure, the member including a generally C-shaped web having spaced apart first and second limbs, each limb having a free end and being interconnected at the opposite end by an intermediate portion, the intermediate portion extending between opposed surfaces of the first and second limbs, the second limb having a face adapted to contact a railway crosstie or other base structure and further having a power rail receiving element, the intermediate portion having a groove, the longitudinal axis of which is disposed normal to the plane of the web, the second limb having an aperture formed in proximity to the free end thereof for receipt of a pin.

A fuller understanding may be had by referring to the following description and claims taken in conjunction with the accompanying drawing in which:

FIG. 1 is a side elevation of the support member and shield according to the invention shown in conjunction with a power rail and a power takeoff arm, FIG. 1 being taken on line 1-1 of FIG. 2;

FIG. 2 is an end elevation of the support member and rail shield; and

FIG. 3 is a perspective view showing the manner in which the rail shield is attached to the support member.

Like reference characters refer to like parts throughout the description of the drawing.

With reference to FIG. 1, the invention is shown incorporated in support member, generally indicated 10. Support member 10 is shown secured to railway crosstie 12 and a power or third rail 14 is shown seated thereon. A takeoff arm or collector shoe 15 of a subway train is shown in contact with power rail 14.

Member 10 includes a web indicated generally 16 having a pair of opposed limbs 18 and 20 interconnected by intermediate portion 22. A plate 24 is formed on the outer side of limb 18. As shown plate 24 commences beyond the free end of limb 18, extends along the length of the limb and

terminates at outer flange 26. Plate 24 is in a plane normal to the plane containing web 16. A plurality of apertures 28 are formed in plate 24 for admission of bolts 30 (FIG. 3) which extend upwardly from crosstie 12 or other base structure such as a concrete floor in a subway tunnel. Plate 24 is secured to the crosstie or like base structure by tightening of nuts 32 into contact with the upper surface of plate 24.

A pedestal 34 (FIG. 3) is formed on the side of limb 18 opposite to plate 24. Pedestal 34 includes a base 36 and a stand 38, the stand being disposed normal to base 36 and in a plane parallel to the plane containing plate 24. Stand 38 is adapted to serve as a seat for insulator cap 40. Insulator cap 40 has a recess 42 formed in its lower surface which is adapted to receive stand 38 therein and a groove 44 formed in its upper surface for receipt of conductor rail 14. Any convenient means may be employed to interconnect rail 14, insulator cap 40 and stand 38.

The intermediate portion 22 of web 16 extends from limb 18 and flares outwards from the plane containing the web to form a support block 46. As shown, support block 46 is positioned approximately midway between limbs 18 and 20. Block 46 is defined in part by surface 48 which in turn defines an element of the inner surface 50 of intermediate portion 22.

The inner surface 50 of portion 22 extends between opposed surfaces 52 and 54 of limbs 18 and 20 respectively. A groove 56 is formed in the surface of support block 46 opposed to surface 54, which groove has a longitudinal axis parallel to the corresponding axis of power rail 14 and disposed at right angles to the plane containing web 16.

An inner flange 58 extends laterally from the plane containing web 16. Flange 58 commences at support block 46 and extends along the lengths of intermediate portion 22 and limb 20. As shown surfaces 50 and 54 of intermediate portion 35 22 and limb 20 respectively are defined in part by flange 58.

A circular aperture 59 is formed in web 16 in proximity to the free end of limb 20. Aperture 59 is positioned approximately midway between diverging limbs of generally V-shaped projection 60. As shown one limb of projection 60 is defined by a portion of flange 58, that portion tapering toward the plane containing web 16 and terminating approximately midway between the inner and outer surfaces of limb 20. The other limb of projection 60 is defined by outer flange 26 which commences at the free end of limb 20 and extends obliquely to surface 54. As seen flange 26 extends beyond projection 60 along limb 20, intermediate portion 22 and terminates at plate 24, flange 26 thereby defining in part the outer surface of web 16.

Shield 62 has an L-shaped portion 64 (FIG. 1) the cross-sectional configuration of which corresponds generally to that of the configuration of flange 58 and a V-shaped portion 66, the cross-sectional configuration of which corresponds generally to the shape of projection 60. Shield 62 terminates at one side at lateral surface 68 (FIG. 3) and at the ends at terminal surfaces 70 and 72. Edge 74 is the dividing line between surfaces 68 and 70. Thus when shield 62 is in the position illustrated in FIG. 1, edge 74 is contained within groove 56 and the surface of the shield contacts flange 58. V-shaped portion 66 is positioned between aperture 59 and projection 60. When so positioned, a pin 76 may be passed through aperture 59 to secure shield 62 to limb 20.

Preferably shield 62 will only assume the position illustrated in FIG. 1, when upward pressure is applied to move the V-shaped portion into contact with projection 60. When the lower portion of the shield is seated in groove 56, the upper portion of the shield preferably must be rotated approximately 10° in order to bring the V-shaped portion 66 into contact with projection 60.

Preferably support member 10 and shield 62 are formed from fiberglass reinforced polyester or similar moldable material. Such material has a high physical strength, satisfactory insulating characteristics and is relatively modest of cost. The material can be readily molded to a desired shape and may be significantly thinner than wood having

comparable strength. A molded section of reinforced polyester serves the same function as the conventional rail shield composed of two separate wooden boards.

Pin 76 may have a metallic core and a rubber coating. Where however a smaller coefficient of friction is required between the pin and the shield as it expands and contracts, the pin may be capped with plastic. In the alternative, the pin may be formed of steel with a grooved section at its center which section contacts the edges of the web defining the aperture thereby ensuring that the pin remains properly positioned.

In use, support members 10 are fastened to railway crossties or the like base structure and so positioned that the distance between adjacent members is slightly greater than the length of each shield. Edge 74 and the corresponding edge at the other end of shield 62 are positioned within grooves 56 of a pair of adjacent members 10 and upward pressure is applied to the V-shaped portion of shield 62 to move the shield into contact with both projections 60 of adjacent members. Pin 76 is then pushed into aperture 59 to secure shield 62 therein. When shield 62 is in such a position, its surfaces at V-shaped portion 66 will contact facing walls of projection 60. It will be evident that a continuous line of shields may be positioned lengthwise along the length of a railway track. The shields will be supported by means of a plurality of members 10 and each shield will be positioned between and supported at each end by a support member each support member supporting the ends of two shields.

It will be understood, of course, that modifications can be made in the preferred embodiment of the present invention as described hereinabove without departing from the scope and purview of the appended claims.

I claim:

1. A support member for supporting a power rail and a rail shield and being adapted to be secured to a railway crosstie or the like base structure, the member including a web having a pair of spaced-apart first and second limbs each having a free end and interconnected at the opposite end by an intermediate portion, the intermediate portion extending between opposed surfaces of the first and second limbs, the first limb having a face adapted to contact the railway crosstie or the like base structure and further having a power rail receiving element, the intermediate portion having an exterior groove, the longitudinal axis of which is disposed normal to

the plane of the web, the second limb having an aperture formed in proximity to the free end thereof and further having an outwardly extending flange spaced apart from said aperture and extending about at least a portion of said aperture, said aperture adapted to receive a pin, the groove in said intermediate portion together with the space between the outwardly extending flange and the pin when received in said aperture both adapted to accommodate portions of said rail shield, and cooperating to removably secure the rail shield to the support member.

2. A support member as claimed in claim 1, wherein said web has an inner flange disposed in a plane normal to the plane of the web said inner flange commencing at the groove and terminating in proximity to the aperture and forming an elongated surface adapted to contact and stabilize the rail shield when accommodated in said groove and space.

3. A support member as claimed in claim 2, wherein said aperture extends generally parallel to said groove and said outwardly extending flange is formed in part by a portion of the inner flange and in part by an outer flange disposed on the side of the second limb opposite the inner flange and commencing at the free end of the second limb, said outwardly extending flange being V in shape.

4. In combination, a support member, a shield and a pin, the support member being adapted to be secured to a railway crosstie or other base structure and including a generally C-shaped web having a pair of spaced-apart first and second limbs, each having a free end and interconnected at the opposite end by an intermediate portion, the intermediate portion having a surface in a plane normal to the plane of the web and extending between opposed surfaces of the first and second limbs, the first limb having a face adapted to contact the rail tie and further having a power rail receiving element, the intermediate portion having a groove, the longitudinal axis of which being disposed normal to the plane of the web, the second limb having an aperture formed in proximity to the free end thereof for receipt of the pin, the shield commencing at a first surface extending in a generally L-shaped and terminating in a V-shaped portion, the shield being so adapted that when the pin is positioned within the aperture, the first surface is positioned within the groove, the L-shaped portion contacts the inner flange and the V-shaped portion is positioned between the V-shaped projection and the pin.
